UNITED STATES PATENT OFFICE

149,172

DESIGN FOR A DOLL

Roger de Vries, Plainfield, N. J.

Application May 10, 1946, Serial No. 129,553

Term of patent 14 years

(Cl. D34—4)

To all whom it may concern:

Be it known that I, Roger de Vries, a citizen of the United States of America, residing at Plainfield, county of Union, State of New Jersey, have invented a new, original, and ornamental Design for Dolls, of which the following is a specification, reference being had to the accompanying drawing, forming part thereof.

Fig. 1 is a front elevational view of a doll showing my new design.

Fig. 2 is a rear elevational view, and

Fig. 3 is a side elevational view thereof, on a reduced scale.

I claim:

The ornamental design for a doll, substantially as shown.

ROGER DE VRIES.
